HARRY F. ROBERTS, OF KAY MOOR, WEST VIRGINIA.

CARBID-LAMP ATTACHMENT.

1,280,849.

Specification of Letters Patent.

Patented Oct. 8, 1918.

Application filed March 5, 1918. Serial No. 220,534.

To all whom it may concern:

Be it known that I, HARRY F. ROBERTS, a citizen of the United States, residing at Kay Moor, in the county of Fayette and 5 State of West Virginia, have invented certain new and useful Improvements in Carbid-Lamp Attachments, of which the following is a specification.

This invention relates to lamps, particularly, to portable gas lamps designed for miners' use, and has for its primary object to provide a lamp of this type burning acetylene gas generated by the action of water on hydrogen carbide with a shield for 15 the burner tip to prevent the flame from being extinguished by currents of air within and without the mine, and by disturbances caused within mines when blasts and shots are fired.

20 To this end the invention consists in the novel construction, combination and arrangement of parts hereinafter described, pointed out in the appended claims and illustrated in the accompanying drawings, 25 in which,

Figure 1 is a front elevation, of an acetylene gas lamp of well known type provided with the improved shield, and,

Fig. 2 is an enlarged cross sectional view 30 on the lines 2—2 of Fig. 1.

In the drawings, 10 indicates a well known type of acetylene gas lamp having a carbide chamber 11 at the bottom, a water holding receptacle 12 at the top and a valve 35 controlled by a stem 13 for regulating the amount of water to be fed to the lower or carbide chamber. Projecting from one side of the lamp 10 is a burner tube 14 upon which is mounted the usual reflector 15, the 40 latter having a sleeve 16 on its rear face that fits over the burner 14 and is secured thereto by a screw 17.

The several parts above described are common to lamps of this type, and in such 45 lamps when the gas issuing from the burner tube 14 is lighted, unless proper care is used to protect the flame it is very liable to be extinguished by slight currents of air. This at times is inconvenient for the user 50 of the lamp, but particularly when the user is without matches or other means for restoring the light and to overcome this difficulty, means are provided to protect the light from complete extinguishment. 55 Means so employed form the subject of the

present invention and comprise a shield 18, preferably made of sheet metal bent into the form shown with a foot 19 bearing upon the front of the reflector and secured thereto by means of a bolt 20 and nut 21. From the 60 foot piece 19 there is an outwardly extending portion 22 lying parallel with the burner tube 14 and forming a side curtain therefor which projects beyond the outer end of the burner where it is bent at a right 65 angle to form the front 23 of the shield which extends across the front of the burner tube and is then bent rearwardly and extends parallel to the curtain 22 on the opposite side of the burner tube, terminating at 70 the reflector and forming a curtain 24 for this side of the burner. The screen 18 is open both above and below the burner tube while in the front 23 is threaded a short section of tubing 25 in line with the opening in the burner tube. The inner end of the tubing 25 is spaced a short distance from the outer end of the burner tube 14 and may be adjusted to and from the burner tube by rotating the same. The opening in 75 the tubular section 25 is greater in diameter than the gas opening in the burner tube 14 so that the flame of the lighted gas passing from the burner tube 14 will extend through the tubular section and project beyond the 80 outer end of the same to give suitable illumination.

In using the lamp, the valve stem 13 is turned to permit the proper amount of water to pass from the reservoir 12 in drops 85 to the carbide holder 11, generating gas in the latter holder which passes outwardly through the burner tube 14. Upon applying a match, or upon operating the self-lighting device 26 which may be found on 90 some of the lamps in present use, the gas is ignited at the end of the burner tube 14, passing through the tubular section 25 and beyond the same, this portion serving as the illuminant and providing a light equally as 95 efficient as the light produced by the lamp without the screen. If the lamp be subjected to currents and drafts or sudden puffs of air that are liable to cause extinguishment of the light, the curtains 18 and 24 will 100 protect the flame where it issues from the burner tube 14 even though the flame beyond the tubular section 25 be blown out. Under these conditions it is only necessary 105 to blow with the breath behind the shield 110

18 to force the flame into the tubular section
25 and cause its projection from the outer
end of said section as before.

5 A shield such as described is simple in
construction, of few parts and may be ap-
plied to any of the well known types of
acetylene gas lamps now on the market and
when a lamp is so equipped it may be car-
ried around with perfect safety, and be
10 protected from absolute extinguishment
however strong the air currents and drafts
liable to be encountered in mines.

Having described my invention, I claim:

15 1. A burner tip shield having parallel
sides and a connecting strip to extend
around the end of a burner tip and spaced
from the end of said tip, and a tubular
member threaded in said connecting strip
and adjustable to and from the burner tip.

20 2. A shield for use with a gas flame to
prevent the total extinction of the flame
thereof comprising a U-shaped member ex-
tending around opposite sides and the front
25 of the burner tip and having means for
holding the same rigidly in place, and a
tubular section threaded in the front of
the shield member having a longitudinal
opening therethrough of greater diameter
30 than the opening in the burner for the pas-
sage of the gas flame.

35 3. In combination with the reflector of an
acetylene gas lamp, of a shield for the
burner of said lamp comprising a strip of
sheet metal bent into U-form to inclose the
tip of the burner and having a foot piece
40 at one side for securing the shield to the
reflector, and a tubular section threaded into
the front of the shield for adjustment to

and from the burner and having a longi-
tudinal opening therethrough of greater 40
diameter than the opening in the burner for
the passage of the gas flame.

4. A shield for a gas burner tip made of
sheet metal bent into U-form with straight
parallel sides and a straight connecting por-
tion perpendicular of said sides, a foot piece
extending outwardly from one of said sides,
means for securing the foot piece to a sup-
port for rigidly holding the shield around
the burner, and a short tubular section 50
threaded in the connecting strip of the
shield having a longitudinal opening there-
through adapted to be alined with the open-
ing in the burner through which the flame
of the burner is adapted to pass. 55

5. A device for preventing the total ex-
tinction of a gas flame by air currents com-
prising an angular shield adapted to be se-
cured to the burner support and covering
opposite sides and the front of the burner 60
tip, said shield being spaced at the front
from the end of said tip and entirely open
at the top and bottom, and a tubular member
spaced from the burner supported in the
front of said shield and adjustable to and 65
from the burner tip, said tubular member
having an opening therethrough larger than
the opening in the burner tip and in aline-
ment therewith through which opening the
gas flame is adapted to pass. 70

In testimony whereof I affix my signature
in presence of two witnesses.

HARRY F. ROBERTS.
